United States Patent [19]
Sandberg

[11] Des. 268,164
[45]  Mar. 8, 1983

[54] JAR LID OPENER

[76] Inventor: Robert R. Sandberg, P.O. Box 232, Prineville, Oreg. 97754

[] Term: 14 Years

[21] Appl. No.: 198,877

[22] Filed: Oct. 20, 1980

[51] Int. Cl. .... D07—99

[52] U.S. Cl. D8/40; 81/3.43

[58] Field of Search D8/40, 34, 33, 21, 22;
81/3.43, 64, 68

[56] References Cited

U.S. PATENT DOCUMENTS

1,631,689 6/1927 Moser 81/3.43
2,132,207 10/1938 Donovan ..... D8/21 X

2,481,055 9/1949 Whitaker 81/3.43
3,678,788 7/1972 Matti 81/3.43

Primary Examiner—Joel Stearman

Assistant Examiner—Carmen H. Vales

Attorney, Agent, or Firm—Kolisch, Hartwell &
Dickinson

[57] CLAIM

The ornamental design for a jar lid opener, as shown and described.

DESCRIPTION

FIG. 1 is a top plan view of a jar lid opener showing my new design, the bottom plan view is a mirror image thereto;

FIG. 2 is a right side elevational view thereof;

FIG. 3 is a left side elevational view thereof; and

FIG. 4 is a perspective view thereof, the broken line showing of a jar is for illustrative purposes only.

FIG. 3

FIG. 2

FIG. 4